(57) **CLAIM**

The ornamental design for a battery module case, as shown and described.

DESCRIPTION

FIG. 1 is a front elevational view of the battery module case; FIG. 2 is a rear elevational view thereof; FIG. 3 is a left-side elevational view thereof;

FIG. 4 is a right-side elevational view thereof; FIG. 5 is a top plan view thereof;

FIG. 6 is a bottom plan view thereof;

FIG. 7 is a top, front perspective view thereof;

FIG. 8 is a bottom, front perspective view thereof;

FIG. 9 is a top, rear perspective view thereof;

FIG. 10 is a top, right perspective view thereof;

FIG. 11 is a top, left perspective view thereof;

FIG. 12 is a cross-sectional view along line A-A in FIG. 1;

FIG. 13 is a cross-sectional view along line B-B in FIG. 1;

FIG. 14 is a detail view of the area demarcated by line C-C in FIG. 12;

FIG. 15 is a detail view of the area demarcated by line D-D in FIG. 12;

FIG. 16 is a detail view of the area demarcated by line E-E in FIG. 13;

FIG. 17 is a detail view of the area demarcated by line F-F in FIG. 13;

FIG. 18 is a detail view of the area demarcated by line G-G in FIG. 10;

FIG. 19 is a detail view of the area demarcated by line H-H in FIG. 10;

FIG. 20 is a detail view of the area demarcated by line I-I in FIG. 11; and,

FIG. 21 is a detail view of the area demarcated by line J-J in FIG. 11.

The evenly spaced broken lines depict unclaimed parts of the battery module case and form no part of the claimed design. The dot-dash chain lines indicate the cross-sectional lines and the detail view lines, and form no part of the claimed design.
